UNITED STATES PATENT OFFICE

102,008

DESIGN FOR A JAR

Frasier Smith, Wheeling, W. Va., assignor to Hazel-Atlas Glass Company, Wheeling, W. Va., a corporation of West Virginia

Application September 30, 1936, Serial No. 65,084

Term of patent 7 years

To all whom it may concern:

Be it known that I, Frasier Smith, a citizen of the United States, residing at Wheeling, in the county of Ohio and State of West Virginia, have invented a new, original, and ornamental Design for a Jar, of which the following is a specification, reference being had to the accompanying drawing, forming part thereof.

I claim:

The ornamental design for a jar, as shown.

FRASIER SMITH.
